CLAIM

The ornamental design for a integrated magnified optical sight and reflex sight device, as shown and described.

DESCRIPTION

FIG. 1 is a perspective view of an integrated magnified optical sight and reflex sight device showing my new design.

FIG. 2 is a front view of the integrated magnified optical sight and reflex sight device.

FIG. 3 is a rear view of the integrated magnified optical sight and reflex sight device.

FIG. 4 is a right view of the integrated magnified optical sight and reflex sight device.

FIG. 5 is a left view of the integrated magnified optical sight and reflex sight device.

FIG. 6 is a top view of the integrated magnified optical sight and reflex sight device; and,

FIG. 7 is a bottom view of the integrated magnified optical sight and reflex sight device.
